UNITED STATES PATENT OFFICE.

HENRY L. VENN, OF RIVER FOREST, ILLINOIS, ASSIGNOR TO CENTURY RUBBER WORKS, OF CICERO, ILLINOIS, A CORPORATION OF ILLINOIS.

DESIGN FOR A TIRE.

Application filed October 1, 1928. Serial No. 28,345. Term of patent 7 years.

To all whom it may concern:

Be it known that I, HENRY L. VENN, a citizen of the United States, and a resident of River Forest, county of Cook, and State of Illinois, have invented a new, original, and ornamental Design for a Tire, of which the following is a specification, reference being had to the accompanying drawing, forming a part thereof, and wherein—

Fig. 1 is a top plan view of a portion of a tire embodying my design and Fig. 2 is a cross section through the tire as taken on the line 2—2 of Fig. 1.

I claim:

The ornamental design for a tire substantially as shown.

HENRY L. VENN.
